ATTORNEY.

UNITED STATES PATENT OFFICE.

FRANK M. STOLL, OF DENVER, COLORADO.

COLLAPSIBLE BED.

Application filed September 26, 1921. Serial No. 503,270.

To all whom it may concern:

Be it known that I, FRANK M. STOLL, a citizen of the United States, and a resident of Denver, in the county of Denver and State of Colorado, have invented certain new and useful Improvements in Collapsible Beds; of which I do declare the following to be a full, clear, and exact description of the same, such as will enable others, skilled in the art to which it appertains, to make and use my invention, reference being had to the accompanying drawings, and to the reference numerals marked thereon, which form a part of this specification.

15 The invention relates to improvements in collapsible beds, particularly of the type adapted to be folded into a small compact bundle for carrying in an automobile and used for camping purposes.

20 The principal object of my invention is to provide a bed of this character which will have a minimum of parts, be light in weight, simple in construction, and easily folded or extended.

25 Another object of the invention is to provide a collapsible bed, having a mattress adapted to act as a container for the bed when same is collapsed.

30 A further object of my invention is to provide means for stretching the mattress supporting springs taut with a minimum of effort.

35 A still further object of the invention resides in the detail construction of the collapsible frame work of the bed, whereby the same may be quickly and easily folded and yet when extended will form a rigid and substantial supporting structure.

With these and other objects in view, the 40 invention will now be described in detail, with reference to the accompany drawings.

On the drawings:

Figure 1, is a perspective view of the collapsible bed extended ready for use;

45 Figure 2, is a side elevation of the same partly broken away;

Figure 3, is a sectional view taken on the line 3—3, Fig. 7;

Figure 4, is a detail view of the detachable end of the spring tightening brace;

Figure 5, is a detail plan view showing the operation of the spring tightening lever;

Figure 6, is a side elevation of one of the longitudinal members in its collapsed position;

Figure 7, is a sectional view taken on the line 7—7, Fig. 5;

Figure 8, is a perspective view of the bed in its collapsed position rolled and strapped in the mattress ready for packing or carrying.

Corresponding and like parts are referred to in the following description and indicated in all views of the accompanying drawing by the same reference characters.

Let the numeral 10 represent one of the end bars of the bed and the numeral 11 the other. End bar 10 is stationary when the structure is erected, while end bar 11 is movable lengthwise of the bed for the purpose of stretching or tightening the mattress supporting springs, as will be hereinafter described.

Suspended between the end bars is the usual flexible spring structure 12, upon which is placed the mattress 13. End bar 10 is supported by legs 15 and 16, while the end bar 11 is supported by legs 17 and 18.

A longitudinal member 19 is pivoted to and connects legs 16 and 18, while a similar longitudinal member 20 similarly connects legs 15 and 17, longitudinal members 19 and 20 are U shaped in cross section and are each formed of two parts, pivoted together at the mid-point of each member as shown 25 at 21.

The legs 15, 16, 17 and 18 are L shaped in cross section, and at their upper extremities or points of intersection with the end bars 10 and 11, one of the sides of the L is 90 allowed to extend upward beyond the other and is bent to form a hook 22, as indicated in Fig. 3. In erecting the bed these projecting hooks 22 of each leg are passed through openings 23 formed in the end bars 10 and 11 and are hooked over the edges of the same, the weight of the end bars resting upon the end of the shorter sides of the L shaped legs. A pivoted wedge or clamp 24, attached to the end bars 10 and 11 is now 100 forced into the opening 23 alongside of the hook 22 and effectively prevents its becoming disengaged while the bed is in use. This method of locking the legs is clearly shown in Fig. 3, and is believed to be a new and 105 valuable feature in beds of this type. When it is desired to release the end bars from the legs, the clamp 24 is raised to the broken line position shown in Fig. 7, when the legs can be easily unhooked and detached.

Pivoted to end bar 10 are two diagonal braces 14, which terminate at their free extremities in hook shaped projections 25, which are adapted to engage in openings 5 formed therefor in longitudinal members 19 and 20. In erecting the bed, the hooks 25 of diagonal braces 14 are engaged in their openings in the longitudinal members before the end bar 10 is locked to the legs, as 10 above described, after which time they cannot be disengaged until the end bar 10 is again released from its supporting legs. This end of the bed is erected first.

Pivoted to end bar 11 are two diagonal braces 26, which terminate at their free extremities as shown in Fig. 4; having pins 27 riveted therein, said pins being provided with an upset portion forming a shoulder 28. Each of the pins 27 is adapted to engage in an opening 29 formed in a lever 30 pivoted to each longitudinal member 19 and 20, as shown at 31. The levers 30 normally lie along the top of the longitudinal members 19 and 20 and have two raised portions 25 formed therein, one for holding the pivot hole 29 up, so that it may be engaged by the pivot pins 27, another designated by the numeral 32, forming a hand hold for grasping the lever. The free extremity of the lever 30 is turned downward, as shown at 30 34, to engage in holes 33 formed in the longitudinal members, for the purpose of locking it in place at the two extreme positions of its throw.

35 In erecting this end of the bed, which is erected last, the end bar 11 is placed on, and locked to the legs 17 and 18 as heretofore described; the lever 30 is placed in the position shown in Fig. 6, and in broken lines in 40 Figs. 2 and 5; the legs 17 and 18 are tilted as indicated in broken lines in Fig. 2; the pins 27 are engaged in the openings 29 in the levers 30; the levers 30 are then raised from their locking holes 33 and swung 45 around as indicated by the dotted semi-circle in Fig. 5 to the full line positions, shown in Figs. 2 and 5, when they are again locked in the opposite locking holes, 33. A stop 35 is provided to prevent the lever from being 50 thrown too far. This operation results in moving the end bar 11 from the broken line position in Fig. 5 to the full line position in the same figure which stretches the mattress supporting springs 12 taut ready for use, and effectively locks the whole supporting 55 structure in a rigid position. This lever and method of tightening the springs is believed to be new and valuable and is one of the important features of the invention.

60 The mattress 13 is tied crosswise to allow its being easily rolled; and is provided near one of its extremities with caps 36, which in turn are provided with straps 37.

When it is desired to collapse and pack 65 the bed, the lever 30 is returned to its

former position (the broken line position of Fig. 5), which releases the tension in the springs; end bars 10 and 11 are released from their supporting legs; the diagonal braces 14 and 26 are released from the longitudinal members and folded parallel to and within their respective end bars. One end bar is now revolved coiling the spring supporting structure 12 around it, and laid upon the mattress. The legs are then folded 70 parallel to the longitudinal members, 19 and 20, and the longitudinal members turned upon their pivot point 21 and folded within themselves as shown in Fig. 6. The longitudinal members with their attached legs are 75 equal in length to the width of the bed. The folded longitudinal members are now laid upon the mattress with the spring structure and end bars and the whole rolled with 80 in the mattress. The caps 36 are then 85 slipped over the ends of the bundle thus obtained and strapped together in a compact bundle as shown in Fig. 8. The straps are carried fastened to the mattress so as to be 90 in their proper positions for use.

Projecting pins 38 are carried by the vertical leg of the L-shaped end bars 10 and 11, and bear against each side of each leg and hold same always perpendicular to the end bars.

Having thus described my invention, what I claim and desire to secure by Letters Patent is:—

1. The combination in a bed of the class described, of end bars supporting a flexible 100 spring structure; legs detachably connected to said end bars and adapted to fold within channel shaped longitudinal members; said longitudinal members being hinged near their mid-point and adapted to fold within 105 themselves; diagonal braces pivoted to said end bars and detachably engaging said longitudinal members.

2. The combination in a bed of the class described, of end bars supporting a flexible 110 spring structure; legs detachably supporting said end bars; longitudinal members pivoted to and separating said legs; levers pivotally mounted on said longitudinal members; braces extending from said end bars to said 115 levers and communicating the motion of said levers to said end bars for the purpose of bringing said legs to and locking them in their operative position and also simultaneously stretching said spring structure. 120

3. The combination in a bed of the class described, of end bars supporting a flexible spring structure; legs detachably engaging and supporting said end bars; longitudinal members pivoted to and separating said legs; levers fulcrumed on said longitudinal members; diagonal braces extending from one of said end bars and detachably engaging said longitudinal members; other diagonal braces extending from the opposite 125 130

end bar and detachably engaging said levers for the purpose of communicating the action of said lever to said end bar and legs for the purpose of tightening said spring structure and bringing said legs into operative position.

4. The combination in a bed of the class described, of horizontal, longitudinal members; legs pivoted at each end of said longitudinal members; end members detachably connected to the upper extremities of said legs at the opposite ends of the bed and adapted to support a flexible spring structure; diagonal braces pivoted to one of said end members at their one extremity and being detachably connected to said longitudinal members at their other extremity; means for stretching said flexible spring structure, comprising levers pivoted to said longitudinal members, braces pivoted to one of said end members and detachably engaging said levers; means for locking said levers at their extreme positions.

5. The combination in a bed of the class described, of end bars supporting a flexible spring structure; legs L shaped in cross section detachably engaging said end bars, one side of said L shaped leg being adapted to

support said end bars, the opposite side being adapted to project through an opening 30 formed in said end bars and being provided with a hook-like projection adapted to engage the edge of said opening; pivoted clamps adapted to engage in said openings to prevent said hook-like projections from 35 becoming disengaged; means for rolling said legs perpendicular to said end bars; longitudinal horizontal members separating said legs; diagonal braces extending from said horizontal members to said end 40 bars.

6. The combination in a bed of the class described, of a collapsible supporting structure; a mattress detachably attached to said supporting structure being adapted to roll 45 around and form a container for said bed when same is collapsed and said mattress having caps or hoods and straps attached thereto adapted to fit over the ends of the bundle formed by the collapsed bed and 50 rolled mattress and bind same into a compact bundle.

In testimony whereof, I affix my signature.

FRANK M. STOLL.
